HOLDER FOR GLASS CUTTER

Cephas C. Coleman, St. Louis, Mich.

Application May 14, 1956, Serial No. 584,582

7 Claims. (Cl. 49—52)

This invention relates to glass cutters and particularly to a holder for manual or hand type glass cutters.

Conventional manual or hand type glass cutters are provided with a head having a scoring or cutting member thereon and a handle by which the cutter is manually gripped. In order to facilitate the manual gripping of the cutter by the user, the handle is usually provided with a flattened portion whereby it can be gripped between the thumb and one or more fingers. In using such a cutter, it is difficult to obtain an even and uniform depth cut in the glass. In addition, the glass cutter must be gripped tightly and the effort required to use the cutter may be considerable.

It is therefore an object of this invention to provide a holder for a glass cutter whereby the cutter may be firmly gripped by the user.

It is a further object of this invention to provide such a holder whereby the glass cutter may be used with a minimum of effort by the user.

It is a further object of this invention to provide such a holder which may be easily applied or removed to the cutter.

It is a further object of this invention to provide such a holder which may be readily adjusted to accommodate variations in the size of the glass cutter or other discrepancies in size between the holder and the glass cutter.

In the drawings:

Fig. 1 is a side elevational view of the glass cutter and holder in assembled relationship.

Fig. 2 is a plan view of the same.

Figs. 3 and 4 represent the relative positions of the glass cutter and holder during assembly and disassembly thereof.

Fig. 5 is a diagrammatic representation of the glass cutter and holder as they are used to cut glass.

Fig. 6 is a sectional view taken along the line 6—6 in Fig. 2.

Fig. 7 is a sectional view taken along the line 7—7 in Fig. 2.

Referring to Figs. 1 and 5, a conventional glass cutter comprises a head 10 and a handle 11 extending rearwardly from the head 10. Head 10 is of generally rectangular cross section and has a greater height than thickness. Top edge 12 of head 10 is generally flat (Fig. 5). A cutting element 13, such as a hardened wheel, is rotatably mounted in the outer end 14 of head 10 and end 14 is inclined downwardly and inwardly from top edge 12 of the cutter. Head 10 may also be provided with a multiplicity of teeth 15 in the lower edge thereof which are used to grip the marginal edges of the glass and facilitate its breaking along a straight line after being scored by the cutting wheel 13.

Handle 11 is connected to head 10 at the rear end thereof. End section 16 of handle 11 adjacent head 10 is generally flat and wide, the thickness thereof being several times less than the height of head 10 (Fig. 1). The sides of end section 16 diverge toward head 10 and converge toward central section 17 of the handle. The

cross section of central section 17 of handle 11 is generally oval or rectangular, as shown in Fig. 7. Handle 11 then diverges from central section 17 toward the end. The portion of handle 11 between central section 17 and the outer end has a generally circular cross section. Head 10 and handle 11 are connected by curved portions 18, 19 which extend between flat end section 16 and the top and bottom edges of head 10, respectively.

10 Top and bottom surfaces of end section 16 of the handle provide a finger-engaging portion. A holder 20 is provided in contact with the flat finger-engaging section 16. Holder 20 is made of a single piece of resilient sheet metal such as aluminum and comprises a flat central portion 21 which extends along the top surface of end section 16 of handle 11. Central portion 21 of holder 20 has substantially the same shape as end section 16. A lip 22 extends along one edge of central portion 21 and an inwardly turned flange 23 extends along the other edge thereof and encircles end section 16 of handle 11. Holder 20 generally encircles flat section 16 of handle 11 except for a diagonal slot 24 between lip 22 and the edge of flange 23. The minimum width W of slot 24 is less than the diameter D of the part of handle 11 between central section 17 and the outer end but is greater than thickness T of central section 17 (Figs. 2, 4 and 7).

The holder thus includes a first portion, at the end of flange 23 which is adjacent head 10, defining an enlarged resting area for the middle finger of an operator 30 and a second portion 24a defining a thumb-engaging surface.

A tab 25 extends outwardly from inwardly turned flange 23 and contacts curved portion 19 at the area of juncture of head 10 and handle 11. Holder 20 is also 35 provided with a tab 26 which extends outwardly from central portion 21 and contacts top edge 12 of head 10.

Referring to Fig. 5, the glass cutter with the holder attached may be readily gripped by the user by placing the thumb against tab 25 and the middle finger against tab 26. The glass cutter may then be readily moved along the surface of a sheet of glass S, causing scoring wheel 13 to cut a line in the surface of the sheet. The holder permits the glass cutter to be more readily gripped and a minimum of effort is required to move the cutter along the surface of the glass.

Referring to Figs. 3 and 4, holder 20 may be removed from the cutter by moving the cutter bodily to the left relative to the holder; and, as central section 17 of the cutter handle approaches the narrowest portion of slot 24, the cutter is rotated 90° relative to the holder, permitting the cutter to be slipped out of the holder through slot 24. As previously mentioned, the width of slot 24 at the narrowest point is less than the diameter D of the portion of the handle extending between the central section 17 and the outer end of the handle; but the width is greater than the thickness T of the central section 17. By this construction, it is impossible to remove the holder merely by moving the glass cutter relative to the holder; it is also necessary to rotate the cutter 90° relative to the holder. This construction prevents the holder from becoming inadvertently detached from the cutter.

The holder may be again applied to the cutter by the reverse procedure, namely, inserting the central section 17 of the cutter handle through slot 24, as shown in Fig. 4, and rotating the cutter 90° relative to the holder, bringing end section 16 into the position shown in Fig. 3 and thereafter moving the cutter to the right relative to the holder to bring lip 22 and inturned flange 23 into contact with central section 16 of the cutter handle. Since the holder is made of spring material, curved portion 24 applies a spring pressure to top edge 12 of the cutter head and thereby maintains the holder in position

on the glass cutter. The gripping force may be readily adjusted by bending curved portion 24a relative to central portion 21 of the holder. Such an adjustment may be necessary to accommodate variations in the size of the cutter or other discrepancies in size between the holder and glass cutter.

It can thus be seen that I have provided a holder which may be easily and readily applied or removed and which provides a means for firmly gripping the glass cutter. With the holder attached, the glass cutter may be used with a minimum of effort providing a uniform cutting. The holder may be manufactured at low cost and is so constructed that it can be readily adjusted to accommodate variations in the size of glass cutters. The holder may be made of metal or plastic.

I claim:

1. The combination comprising a glass cutter having a head and a handle connected to one end of said head, said head being generally rectangular in cross section, a cutting element rotatably mounted on the other end of said head, said handle having a finger-engaging portion adjacent said head, said finger-engaging portion comprising generally flat parallel surfaces extending generally longitudinally of said handle with the edges thereof converging toward the central portion of the handle away from said head, the portion of said handle between the central portion thereof and the end thereof being generally circular and diverging, a holder removably mounted on said glass cutter and comprising a complementary portion encircling said finger-engaging portion of the handle, said holder including a first portion thereof overlying said head, said first portion being greater in width than said head and providing a finger-engaging surface, a second portion thereof underlying the handle, said second portion being greater in width than said head and providing a thumb-engaging surface, said finger-engaging surfaces being generally parallel to each other and generally parallel to the axis of rotation of said cutting element.

2. The combination comprising a glass cutter having a head and a handle connected to one end of said head, said head being generally rectangular in cross section, a cutting element rotatably mounted on the other end of said head, said handle having a finger-engaging portion adjacent said head, said finger-engaging portion comprising generally flat parallel surfaces extending generally longitudinally of said handle with the edges thereof converging toward the central portion of the handle away from said head, the portion of said handle between the central portion thereof and the end thereof being generally circular and diverging, a holder removably mounted on said glass cutter and comprising a complementary portion encircling said finger-engaging portion of the handle, a first portion extending from said complementary portion overlying said head, said first portion being greater in width than said head and providing a finger-engaging surface, a second portion extending from said complementary portion underlying the handle, said second portion being greater in width than said head and providing a thumb-engaging surface, said finger-engaging surfaces being generally parallel to each other and generally parallel to the axis of rotation of said cutting element, and a finger-engaging tab extending outwardly from each said portion, said first portion of said holder applying a yielding force to the head of said cutter.

3. The combination set forth in claim 2 including a slot extending diagonally of said encircling portion whereby said holder may be removed from said glass cutter by shifting said holder longitudinally relative to said glass holder away from said head, twisting said holder relative to said glass cutter and moving said glass cutter through said slot away from said holder.

4. The combination comprising a glass cutter having a head and a handle connected to one end of said head,

said head being generally rectangular in cross section, a cutting element rotatably mounted on the other end of said head, said handle having a finger-engaging portion adjacent said head, said finger-engaging portion comprising generally flat parallel surfaces extending generally longitudinally of said handle with the edges thereof converging toward the central portion of the handle away from said head, the portion of said handle between the central portion thereof and the end thereof being generally circular and diverging, a holder of resilient material removably mounted on said glass cutter and comprising a complementary portion encircling said finger-engaging portion of the handle, said complementary portion comprising a central portion having diverging edges, a lip extending along one edge of said central portion, a flange extending along the other edge of said central portion and having a part thereof parallel to, spaced from and overlying said central portion, the longitudinal edge of said flange being spaced from the free edge of said lip to define a diagonally extending slot through which the handle of a glass cutter may be passed in order to mount the holder on a glass cutter, a first portion extending from the central portion of said complementary portion, said first portion being greater in width than said head and providing a finger-engaging surface parallel to the axis of rotation of said cutting element, a second portion extending from said flange of the complementary portion underlying the handle, said second portion being greater in width than said head and providing a thumb-engaging surface parallel to the axis of rotation of said cutting element, said finger-engaging surface being spaced laterally from said complementary portion, said thumb-engaging portion lying in substantially the same plane as the complementary portion.

5. A holder for a glass cutter having a head, a handle and a cutting element rotatably mounted on the head, which holder comprises a central portion having diverging edges, a lip extending along one edge of said central portion, a flange extending along the outer edge of said central portion and having a part thereof parallel to, spaced from and overlying said central portion, whereby said holder may be mounted on a cutter with said lip, central portion and flange encircling the handle of the cutter, said holder including a first portion extending longitudinally from the central portion of the holder and defining a surface parallel to and spaced from the plane of the central portion which surface provides an enlarged resting area for the middle finger of an operator, said holder including a second portion extending longitudinally of the holder from said part of the flange which is parallel to the central portion of the holder and in the same direction as the first portion of the holder, said second portion defining a thumb-engaging surface, a tab extending outwardly from the end of said first portion and another tab extending outwardly from the end of said second portion.

6. The combination set forth in claim 5, said flange having a free longitudinal edge and said lip having a free longitudinal edge, the longitudinal edge of said flange being spaced from the free edge of said lip to define a diagonally extending slot through which the handle of a glass cutter may be passed in order to mount holder on a glass cutter.

7. A holder for a glass cutter having a head, a handle and a cutting element rotatably mounted on the head, which holder comprises an encircling portion for mounting the holder on the handle of the glass cutter, a first portion extending from said encircling portion and adapted to overlie the head of the glass cutter, said first portion having a substantial width greater than the head of the glass cutter to thereby provide an enlarged finger-engaging surface overlying the head of the glass cutter, and a second portion extending from said encircling portion and displaced longitudinally relative to said first portion, said second portion being of substantial width

to thereby provide an enlarged thumb-engaging surface parallel to and spaced laterally and longitudinally from said finger-engaging surface formed by said first portion.
